CLAIM

The ornamental design for a shower caddy extender, as shown and described.

DESCRIPTION

FIG. 1 is a perspective view of a shower caddy extender showing our new design, the broken-line disclosure of a portion of a shower caddy being for illustrative purposes only and forming no part of the claimed design; FIG. 2 is a front elevational view thereof; FIG. 3 is a right side elevational view thereof; FIG. 4 is a rear elevational view thereof; FIG. 5 is a left side elevational view thereof; FIG. 6 is a top plan view thereof; and, FIG. 7 is a bottom plan view thereof.
